UNITED STATES PATENT OFFICE

CRAWFORD C. LOOMIS, OF ILION, NEW YORK, ASSIGNOR TO REMINGTON ARMS COMPANY, INC., A CORPORATION OF DELAWARE

FIREARM

Application filed September 11, 1930. Serial No. 481,277.

This invention relates to firearms, and particularly to a fore-end construction for firearms. For the purpose of illustration, the invention has been shown as applied to a fire-
5 arm of the type described in the patent to Browning, No. 812,326, February 13, 1906, although in many aspects it is of general application and not limited to the Browning construction.

10 In firearms of this type the fore-end abuts the forward end of the receiver, and is channeled to receive the lower part of the barrel, which recoils with respect to the fore-end and the receiver to perform the operations incident to ejecting a fired cartridge and reloading. The cartridges are contained in a tubular magazine arranged below the barrel and substantially enclosed within the fore-end.

In the Browning patent the fore-end is 20 channeled throughout its length and the magazine tube extends entirely through and slightly beyond the fore-end. One purpose of this construction is to enable the fore-end to be retained in place by means of a cap 25 screw threaded upon the projecting end of the magazine tube.

It is an object of the present invention to improve such a fore-end construction with a view to completely enclosing the magazine 30 tube within the fore-end and to provide an effective fastening device for a magazine tube and fore-end so constructed.

In the drawings:

Fig. 1 is a fragmentary side elevation, 35 partly in section, of a firearm embodying the invention.

Fig. 2 is a section on the line 2—2 of Fig. 1.

Fig. 3 is a sectional elevation of a part of the fore-end securing device.

40 Fig. 4 is an elevation at the left end of Fig. 5.

Fig. 5 is a fragmentary longitudinal side elevation, partly in section, showing a modification of the invention.

45 The firearm comprises a barrel 10, a receiver 11, and a fore-end 12, the rearward end of the fore-end 12 abutting the forward end of receiver 11 and preferably being provided with a tenon to be received in a recess in the receiver as clearly shown in Fig. 1. Rigidly

secured to the barrel 10 is an apertured lug 13 which encircles the forward end of the magazine tube 14. When the gun is fired, the barrel recoils with respect to the receiver and the fore-end, compressing the recoil spring 15 which encircles the magazine tube. A suitable friction ring device, indicated generally by the numeral 16, may be interposed between recoil spring 15 and the barrel lug 13. After the completion of the recoil movement of the barrel, it is thrust forward to the position illustrated in Fig. 1 by the spring 15 and is stopped in its home position by the engagement of the forward side of lug 13 with the adjacent face of the fore-end 12. The spring 15 necessarily exerts considerable force upon the barrel so that at the time the face of the lug 13 contacts with the fore-end said lug is moving with considerable speed. The shock of stopping the barrel is thus transmitted to the fore-end and the devices which secure the fore-end in place must be so arranged as to receive and distribute the shock without damage. Since wood is the ordinary material for the fore-end and, indeed, appears to be the only practicable material, the matter of receiving and properly distributing the recoil shock without damage to the wood becomes one of major importance.

As heretofore stated, these firearms as hitherto constructed have included a magazine tube rigidly secured in the receiver and extending throughout the length of the fore-end so that a cap screw could be applied to the forward end of the tube, bearing against the front face of the fore-end, thereby holding it in place and transmitting the strain received from the fore-end to the receiver. The magazine tube being of relatively large diameter, the base of the cap screw had a broad bearing upon the fore-end and the recoil shock was transmitted with comparative ease. This construction, however, is objectionable in that it requires that substantially the same diameter of the fore-end be maintained throughout its length and that it terminate in an abrupt front face adapted to form a wide bearing for a large cap screw. Such a firearm does not have a desirable appearance and, further, a gap or notch is left between

the cap screw and the barrel, which is objectionable particularly when the gun is used in the brush by reason of its tendency to catch and hold twigs, leaves, and other foreign objects.

5 The present invention contemplates housing the magazine tube entirely within the fore-end and providing an improved fastening device of desirable appearance which enables the fore-end to terminate in a curving line, rather than with the abrupt and angular contour of the prior art. To this end, the magazine tube terminates a short distance in front of the barrel lug 13 and its end is closed 10 by a threaded plug 17. Said plug is apertured, preferably eccentrically, and threaded to receive the threaded end of a take-down bolt 18 which extends longitudinally through a bore of relatively small diameter in the forward part of the fore-end. The take-down bolt is provided with a milled head 19 and, since a snug fit, necessitating considerable torque, is desirable, the head 19 is traversed by a projectable pin 20 yielding held in 15 place by a plunger 21 pressed into a recess 22 in the pin 20 by a spring 23 which abuts a screw 24 threaded into a suitable aperture in the head 19. By pressing upon either end of the pin 20 the plunger 21 is retracted against 20 the force of its spring and the pin may be moved downwardly from one edge of the head 19, thereby forming a convenient handle for properly loosening and tightening the take-down bolt.

25 To properly distribute the recoil shock for transmission to the head of the take-down bolt, a metal liner 25 for the bolt receiving recess is provided. Said liner terminates in a flanged head 26, preferably of the same diameter as the take-down screw head 19 and received in a recess in the fore-end so that its exposed face lies flush with the fore-end, and the take-down bolt appears to seat directly upon the fore-end. To yieldingly retain the take-down bolt against accidental loosening, a spring pressed ball or pin 27 is inserted in a suitable recess in the head and engages in any of a plurality of depressions or recesses in the flange 26. To prevent the take-down bolt from falling out when the gun is taken down, a portion 28 of the shank of said bolt is of reduced diameter and a screw 29 passes transversely through the fore-end and an aperture in the liner 25, its projecting end being received opposite the section 28 of the take-down bolt. The shoulders at the ends of said sections form abutments which, engaging the end of the screw 29, limit the longitudinal movement of the take-down bolt. To take the gun down, the pin 20 is projected from one side of the head 19 to afford the necessary leverage for loosening the take-down bolt, and the take-down bolt is then rotated to disengage its threaded end from the plug 17 in the magazine tube which,

it will be recalled, is rigidly secured to the receiver. The fore-end can then be drawn forward to clear the end of the magazine tube and be moved downward. The barrel is then drawn forward out of the receiver, the lug 13 passing off from the end of the magazine tube in this operation.

75 In the modification illustrated in Figs. 4 and 5 the construction is similar to that already described except that the head 35 of the take-down bolt is eccentric to the shank of said bolt, so that when the gun is assembled said head lies closely adjacent to the underside of the barrel, instead of leaving a gap between the head and the barrel. If said gap is considered undesirable, the construction of Figs. 4 and 5 may be used. This arrangement has a further advantage, in that the pin 20 may be arranged to project a short distance from the head 35 when the parts 80 are assembled and thereby form a lock for preventing accidental loosening of the take-down bolt by engaging the side of the barrel, as clearly shown in Fig. 4.

85 It is to be understood that the construction described and illustrated is merely a representative embodiment of an invention which may take many other forms all falling within the scope of the appended claims.

90 What is claimed is:

95 1. In a firearm comprising a barrel, a magazine tube extending parallel to said barrel, and a fore-end housing said magazine tube; means for securing said fore-end in place comprising a bolt traversing said fore-end 100 and removably secured to said magazine tube.

105 2. In a firearm comprising a barrel, a receiver and a fore-end; a magazine tube secured to said receiver extending into and terminating within said fore-end, and means for securing said fore-end to said magazine tube while permitting relative movement of the barrel and fore-end.

110 3. In a firearm comprising a receiver and a fore-end, a fore-end fastening device comprising an element secured in said receiver and terminating within said fore-end, and a device traversing a portion of said fore-end in a direction longitudinally of said fore-end and removably connected with said element.

115 4. In a firearm, a receiver, a fore-end, a magazine tube housed and terminating within said fore-end, a plug in the end of said 120 magazine tube having therein a threaded aperture, a threaded bolt traversing the forward part of said fore-end adapted to be received in said threaded aperture, and means for manipulating said bolt.

125 5. In a firearm, a receiver, a fore-end, a magazine tube housed and terminating within said fore-end, a plug in the end of said 130 magazine tube having therein a threaded aperture, and a threaded bolt traversing the

forward part of said fore-end adapted to be received in said threaded aperture, the head of said bolt bearing against the end of said fore-end.

5 6. In a firearm, a receiver, a fore-end, a magazine tube housed and terminating within said fore-end, a plug in the end of said magazine tube having therein a threaded aperture, a threaded bolt traversing a bore 10 in the forward part of said fore-end and adapted to be received in said aperture, and a liner in said bore encircling said bolt and terminating in a flange adapted to form a bearing for the head of said bolt.

15 7. In a firearm, a receiver, a fore-end, a magazine tube housed and terminating within said fore-end, a plug in the end of said magazine tube having therein a threaded aperture, a threaded bolt traversing the 20 forward part of said fore-end adapted to be received in said threaded aperture, and means for manipulating said bolt, said means comprising a pin projectable transversely from the head of said bolt and serving as a lock to prevent accidental loosening 25 of said bolt.

8. In a firearm, a receiver, a fore-end, a magazine tube housed and terminating within said fore-end, a plug in the end of 30 said magazine tube having therein a threaded aperture, a threaded bolt traversing the forward part of said fore-end adapted to be received in said threaded aperture, and means for retaining said bolt in said fore-end 35 when it is disengaged from said plug.

9. In a firearm, a take-down bolt having a head provided with a transversely extending pin adapted to be projected from said head to afford increased leverage, means for yieldingly retaining said pin in retracted position and limiting its movement in extended position, and means projecting longitudinally from said head adapted to yieldingly retain it against rotation when the firearm 45 is assembled.
